CLOSURE DEVICE

Henry Tyska, Vails Gate, N. Y.

Application December 14, 1950, Serial No. 200,740

2 Claims. (Cl. 70—167)

1

The present invention relates to an improved closure device and it relates more particularly to an improved closure device of the self retaining type which is advantageously applicable to the orifices of automobile gasoline tanks, radiators or any other container orifices to which access is regularly required.

The devices now generally employed in the automotive field for the closing of the gasoline tank or radiator orifices are of the bayonet type wherein the closure is provided with one or more radial projections or lugs and the orifice neck is provided with corresponding bayonet grooves each consisting of a longitudinal groove or slit joined to a sloping peripheral groove or slit and terminating at the orifice. In order to apply this closure to an orifice, it is necessary to bring the lugs into registry with the orifice ends of the corresponding bayonet grooves, depress the closure and then twist it to complete the operation of closing the orifice. It is apparent that this closing operation is at its best awkward and time consuming. Furthermore, failure to complete all the required steps often results in a lost closure and since the use of these closures is regular such losses are common. There have been many attempts to overcome the aforesaid drawbacks of the bayonet type closure device but these attempts have resulted in devices which are either too complex and expensive or have failed to overcome these drawbacks and hence have not been commercially adopted.

An object of the present invention is to provide an improved closure device of the snap-on self-retaining type which may be easily locked in a closed position.

A further object of the present invention is to provide an improved closure device of the snap-on self-retaining type which is of rugged and inexpensive construction and which is substantially foolproof in operation.

Still a further object of the present invention is to provide an improved closure device of the snap-on self-retaining device in connection with an orifice neck adapter for converting the bayonet or other type of orifice neck for use with the improved closure device.

The above and other objects of the present invention will become apparent from a reading of the following description taken in conjunction with the accompanying drawings, wherein:

Fig. 1 is a top plan view of the improved closure device in combination with an auxiliary orifice tube as applied to a container orifice;

Fig. 2 is a front elevational view partially in section;

2

Fig. 3 is a sectional view along line 3—3 of Fig. 2;

Fig. 4 is a fragmentary sectional view of the container orifice;

Fig. 5 is a sectional view along line 5—5 in Fig. 6;

Fig. 6 is a sectional view along line 6—6 in Fig. 5;

Fig. 7 is a front elevational view illustrating the closure device disassembled from the auxiliary orifice tube.

The present invention broadly contemplates a closure device comprising a hollow body member having a cylindrical wall in which there is formed a plurality of apertures, detents radially movable relative to said cylindrical wall and protruding through said apertures, and resilient means formed of a strip of spring material and shaped to nest within said body member and to press against said detents to urge the same radially outwardly. This closure device is applicable to a corresponding orifice neck or spout of a suitable size adapted to receive the closure device, having its edge portion upwardly and outwardly flanged so as to urge the closure detents inwardly as the closure device is applied and having a peripheral groove of concave cross section relative to the inner face of the wall and adapted to permit the outward movement of the detents and hence the sealing of the orifice and the retention of the closure device. The orifice or neck may be a separate component provided with means for attaching to the usual bayonet type of orifice neck thus permitting the adaptation of the usual orifice for use with the improved closure device. An arrangement is provided to permit the locking of the closure device and its removal from the orifice only with the corresponding key.

Reference is now made to the drawings and more particularly to Figs. 1—6 thereof, which illustrate a preferred embodiment of the present invention, wherein 10 designates the orifice neck or spout to which the improved closure device is to be applied and which communicates with an automobile radiator, gasoline tank or other container requiring periodic access. The upper end of the neck 10 is of the common construction affording a pair of oppositely disposed bayonet slots and consists of an inwardly projecting circular flange 11 provided with depending portions 12, the bottom edges 13 of which slope upwardly in a counter-clockwise direction as viewed in Fig. 3 to cut out lug receiving portions 14. Furthermore, the lower portions of the edges 13 terminate in stop members 16 which

are integral extensions of the depending portions 12.

An auxiliary or supplementary orifice tube 17 is provided which is constructed to accept the improved closure device and which may be easily coupled to the orifice neck 10. The orifice tube 17 includes an upper section 24 connected to a tubular coupling member 18 of smaller cross section having a diameter slightly less than that of the inner edge of the flange 12. Moreover, a pair of oppositely disposed lugs 15 which project radially outwardly are integrally formed in the coupling member 18. Further, the upper edge of the coupling member 18 is connected by means of a substantially flat shoulder 19 to the wall 20 of the upper portion 24. The wall 20 is of substantially S-shaped cross section as viewed on the right side of Fig. 5 to provide an arcuate groove 21 in the inner face of the wall 20, a re-entrant portion 22 and an outwardly sloping upper portion 23. The auxiliary orifice tube 17 may be formed of sheet steel or any other suitable material and is attached to the neck 10 by bringing the lugs 15 into registry with the cutouts 14, inserting the member 18 into the neck 10 and then twisting the auxiliary orifice tube 17 clockwise so that the lugs engage the sloping edge 13 of the depending portions 12 to urge the shoulder 19 and the upper face of the flange 11 toward each other. An annular gasket of suitable material is disposed between the confronting faces of the shoulder 19 and the flange 11 in order to insure a substantially noiseless and fluid tight seal. A self-tapping screw is passed through the shoulder 19, the gasket 26 and the flange 11 in order to securely lock the auxiliary orifice tube in position.

A closure device 30 of the present improved construction is slidably hinged to the auxiliary orifice tube 10 by means of a pair of spaced slotted elements 32 which depend from the closure device 30. The slots in the elements 32 are engaged by a pin 33 which is secured to the auxiliary orifice tube thus permitting the raising of the closure device 30 and its swinging away from the orifice, thus permitting free access thereto.

The closure device 30 includes a cup shaped body member 34 having a cylindrical wall 36 the upper edge of which is provided with an outwardly projecting peripheral flange 37. A plurality of angularly spaced circular apertures 38 are formed in the cylindrical wall 36 at substantially the same level. Associated with each of the apertures 38 is a spherical or ball detent 35 of slightly larger diameter than the aperture diameter, the spherical detents being disposed in the body member 34 and normally protruding through the apertures 38. Resilient means 39 formed of a strip of spring material, preferably spring steel or the like, is nested in the body member 34. The resilient means 39 are provided with recessed portions 40 which abut the inner faces of the detents 35 and are sprung to urge the spherical detents radially outwardly until they normally rest in the circular apertures 38. Since, in the present embodiment, three detents are illustrated, the resilient means assumes the shape of a triangle having rounded corners which abut the inner face of the cylindrical wall 36 and sides which abut the detents 35. However, it is obvious that any other number of detents 35 may be employed and the resilient means assume a correspondingly different shape. Furthermore, while the detents 35 have been illustrated as spherical or ball shaped, they may be of any other suitable shape.

The upper open end of the body member 34 is closed by a cap member 41 of convexo-concave shape provided with a flat annular shoulder 42 which terminates in a depending peripheral collar 43. The cap member 41 fits over the flange 37 which is preferably force fit within the collar 43 into abutment with the shoulder 42. The cap member 41 and body member 34 may be received in assembled position by welding or other suitable means. Furthermore, a centrally positioned circular aperture is formed in the cap member 41.

A locking mechanism 43 is disposed within the body member 34 and includes a collar or sleeve member 44 which is supported from the cap member 41 and communicates with the circular aperture formed in the cap member. A rotatable cylinder 45 is positioned in the sleeve 44 and is provided with any well known type of tumbler mechanism and a key way 46 accessible through the aperture in the cap member 41. Depending axially from the lower end of the cylinder 45 is the shaft 47 on which is mounted a locking cam 48 rotatable with the cylinder 45 and secured in position by a horseshoe locking element 49. The cam 48 is substantially flat and is provided with angularly spaced recessed portions 50 and intervening raised portions 51 each corresponding in number to the number of detents. The recessed portions 50 are so spaced and shaped that when the cam 48 is rotated so that the recessed portions 50 confront the detents 35 they are permitted to move radially inwardly. Thus when the closure device is inserted or removed from the auxiliary closure tube the detents are moved inwardly as they pass along the flange 23 and the reentrant portion 22 and the portions 40 of the resilient means are caused to flex inwardly. When the device 30 is in closed position, the detents 35 are urged outwardly by the resilient means 39 and are forced against the underface of the reentrant portion 22 urging the closure device 30 downwardly and thereby retaining it in closed position. However, when the cam 48 is rotated to bring the raised portions 51 thereof in confronting relationship with the detents 35, the movement of the detents is greatly restricted and they are substantially locked in their outermost position. Thus, when the closure device 30 is inserted in the auxiliary orifice tube 17 and the detents are locked, as aforesaid, the closure device 30 cannot be removed from the orifice tube since the reentrant portion 22 abuts the upper faces of the locked detents 35 and prevents the upward movement of the closure device 30. It should be noted that an annular gasket 54 of any suitable material is supported in the closure device in contact with the underface of the flange 37 in order to effect an acceptable liquid tight closure of the orifice and minimize rattle.

While there has been described and illustrated a preferred embodiment of the present invention, it is obvious that numerous changes and omissions may be made without departing from the spirit thereof. For example, while the closure device has been described and illustrated as hinged to the auxiliary orifice tube 17, it is apparent that these may be separate and unattached.

I claim as my invention:

1. A closure device of the character described comprising a hollow body member having a cylindrical wall, said wall having a plurality of angularly spaced apertures formed therein, a plurality of detents movably disposed within said body member and normally protruding

through said corresponding apertures, resilient means formed of a strip of spring material disposed within said body member and abutting the inner faces of said detents to urge said detents radially outwardly relative to said cylindrical wall and a cam member mounted within said body member and rotatable about the longitudinal axis of said cylindrical wall and at the level of said detents said cam member having a raised portion which may be brought into close 10 confronting relationship with at least one of said detents to lock said detent in its substantially outermost position.

2. A closure device of the character described comprising a cup shaped body member having a 15 cylindrical wall, said wall having a plurality of angularly spaced circular apertures formed therein, a circular cap member coaxially secured to the open end of said body portion and having its periphery extending radially beyond said 20 cylindrical wall, a plurality of spherical detents of greater diameter than said apertures disposed within said body member and normally protruding through said corresponding apertures, resilient means formed of a strip of spring material nesting in said body member and provided with radially recessed portions abutting the inner surfaces of said detents to urge said 25 detents radially outwardly relative to said cylind-

drical wall, said cap having a circular aperture formed therein coaxial with said cap, a sleeve member depending from said cap and coaxial with said cap aperture, a cylindrical member rotatably mounted in said sleeve and having a key receiving slot and a cam member secured to the lower end of said cylindrical member and rotatable therewith said cam member having a plurality of angularly spaced raised portions which may be brought into close confronting relationship with the corresponding detents to lock said detents in their substantially outermost positions.
